UNITED STATES PATENT OFFICE

165,599

WATCH CASE OR SIMILAR ARTICLE

Leon Newhouse, Brooklyn, N. Y., assignor to
Longines-Wittnauer Watch Co., Inc., New York,
N. Y., a corporation of New York

Application November 30, 1950, Serial No. 13,210

Term of patent 14 years

(Cl. D42—8)

To all whom it may concern:

Be it known that I, Leon Newhouse, a citizen of the United States, residing at Brooklyn, county of Kings, and State of New York, have invented a new, original, and ornamental Design for a Watch Case or Similar Article, of which the following is a specification, reference being had to the accompanying drawing, forming a part thereof, wherein:

Fig. 1 is a front plan view of a watch case or similar article showing my new design;

Fig. 2 is a side elevational view thereof;

Fig. 3 is an end elevational view; and

Fig. 4 is a rear plan view of the same.

The essential feature of my design for a watch case resides in the provision of a concentric outer ring spaced a short distance from the main watch case.

I claim:

The ornamental design for a watch case or similar article, substantially as shown and described.

LEON NEWHOUSE.
